WOOD PULP GRINDER

Filed March 9, 1925

UNITED STATES PATENT OFFICE

FRED B. CHAPPELL, OF GLENS FALLS, NEW YORK, ASSIGNOR OF ONE-HALF TO GLENS FALLS MACHINE WORKS, OF GLENS FALLS, NEW YORK, A CORPORATION OF NEW YORK; ANNIE MAE CHAPPELL AND WILLIAM T. COWLES EXECUTORS OF FRED B. CHAPPELL, DECEASED

WOOD-PULP GRINDER

Application filed March 9, 1925. Serial No. 14,065.

This invention relates to certain new and useful improvements in wood pulp grinders and more particularly to the construction of pockets used in connection with multiple pocket grinders such as are now commonly in use, the object being to provide a pocket with removable fingers so that when the fingers become worn, they can be replaced, thereby saving the expense of renewing the whole pocket.

Other and further object of the invention is to provide a pocket with novel means for holding the fingers in their proper position so that the pocket can be adjusted in respect to the grindstone in the usual manner, the fingers being so positioned that they will act to prevent the large slivers from passing through and yet allowing the pulp to pass freely through the fingers.

Other and further objects and advantages of the invention will be hereinafter set forth and the novel features thereof defined by the appended claims.

In the drawings,

Figure 1 is an elevation, partly in section, of the upper portion of a wood pulp grinder;

Figure 2 is a vertical section partly in elevation of one of the pockets;

Figure 3 is a detail vertical section of the pocket;

Figure 4 is a top plan view of a portion of one of the removable finger frames; and

Figure 5 is an elevation of the same.

In the drawings 1 indicates a housing in which is mounted a rotary grindstone 2. Disposed above the housing in a radial manner are pockets 3 into which the wood to be ground is placed and forced against the stone in the ordinary manner and these pockets are provided with a depending apron 4 which is adjustably mounted on the housing 1 by bolts 5.

In constructing the pocket in accordance with my invention, instead of forming the lower edges of the pocket serrated, I provide a cast steel frame 6 having a serrated edge and which I have termed a finger frame which is adapted to be secured in the lower edge of the pocket by bolts or other suitable means against a shoulder 7.

In Figure 1 I have shown a transverse sec-

tion through a pocket with the finger frame in position in order to illustrate the position of the fingers in respect to the grindstone. The finger frame is composed of longitudinal side bars connected together adjacent their ends by cross bars, the lower edges of the cross bars and side bars being serrated to form the fingers and the upper edges of the longitudinal bars are rabbeted as shown at 8 which are adapted to interlock with the rabbeted lower edges 9 of the side walls of the pocket in such a manner that the finger frame can be secured rigidly in position within the pocket so that the pocket can be adjusted towards and away from the grindstone.

In use the operator of a wood pulp grinding machine of this character adjusts the pockets towards and away from the grindstone and it often happens that the pockets are adjusted so as to bring the fingers in contact with the grindstone which of course, wears the fingers away and if this happens several times, it is necessary to replace the entire pocket so that the fingers will be of sufficient length to provide a clearance for the wood pulp and a guard for the large slivers, while with my improved construction of removable fingers, I am able to remove the finger frame and substitute a new one in the pocket, thereby saving the expense of renewing the entire pocket.

From the foregoing description it will be seen that I have provided a pocket for wood pulp grinders formed with a detachable finger frame rigidly secured within the pocket so that it is moved with the pocket as it is adjusted in respect to the grindstone.

What I claim is:

1. A wood pulp grinder having a series of radially disposed pockets and means for adjusting said pockets in respect to the grindstone of said grinder, the side edges of said pockets being rabbeted and a rectangular frame having rabbeted side bars interlocked with the rabbeted edges of said pockets, said pockets being provided with shoulders for engaging the cross bars of said finger frame.

2. A pocket for wood pulp grinders having depending aprons at its ends and provided with internal shoulders, the side edges of said

pockets being rabbeted, a finger frame comprising longitudinally disposed side bars connected together by cross bars adjacent each end, the side bars of said frame being rabbeted and adapted to cooperate with the rabbeted sides of said pockets.

5 In testimony whereof I hereunto affix my signature.

FRED B. CHAPPELL.
